The ornamental design for a soccer mug with a goal, as shown and described.

DESCRIPTION

FIG. 1 is a top perspective view of a soccer mug with a goal illustrating the Applicant's new design;

FIG. 2 is a top view of the soccer mug with a goal;

FIG. 3 is a bottom view of the soccer mug with a goal;

FIG. 4 is a front view of the soccer mug with a goal;

FIG. 5 is a side view of the soccer mug with a goal; and,

FIG. 6 is an enlarged rear view thereof, the rest of the soccer mug with a goal removed for ease of illustration.

Where included, the use of stippling is intended to denote a difference in materials.

The broken lines shown in the figures represent portions of a soccer mug with a goal that form no part of the claimed design.
